LOUD-SPEAKER ARRANGEMENT

Heinrich Benecke, Berlin, Germany, assignor to
 Telefunken Gesellschaft für Drahtlose Tele-
 graphie, m. b. H., Berlin, Germany, a corpora-
 tion of Germany

Application February 10, 1937, Serial No. 124,998
 In Germany February 17, 1936

1 Claim. (Cl. 181—0.5)

In the directed radiation of sound the fact is felt in disturbing manner that the surfaces effecting the directional action are operative only so long as the wavelength is not essentially larger than the linear dimension of the system. If for one reason or another (obstruction of vision) conical and similar guiding surfaces of large dimensions cannot be used, the low frequencies spread unhindered and undirected and cause in many cases, in particular if the ground to be covered is large, disturbances, in particular the doubling of speech. Another great fault is the impossibility to direct low frequencies towards the ground in such a way that they are absorbed beyond even a short distance as in the case for medium and high frequencies with systems of average dimensions.

The invention is concerned with the decrease of too large a range for loud-speakers, particularly of the low frequencies; in other words the sound waves radiated by the loud-speaker should practically be audible for a certain distance only.

This may be accomplished in various manner. The range of the sound waves is limited in accordance with the invention in especially suitable manner by causing the intentional production of strong interferences in a sound field produced by a loud-speaker.

This may, for instance, be accomplished in the manner that with a loud-speaker diaphragm whose radiations are equal on both sides and where with excitation on the one side of the diaphragm the air is compressed, and on the other side rarefied or thinned out, there appear in the plane at right angle to the direction of axis of the diaphragm zones wherein the sound waves are extinguished. The range of extinction increases with increasing distance from the sound source. There are produced in this manner separated by zones of extinction, substantially cone-like regions wherein the sound waves are perceptible. The axes of the regions wherein the sound waves are perceptible, are disposed substantially in the direction of diaphragm axis.

The diaphragm now is orientated with respect to the space or area which is to be covered by the speech in such manner that the axis of the conical region wherein the sound waves are perceptible, is preferably at right angles to the surface to be covered. In this manner a region is insured around the sound source wherein the sound waves are perceptible and which is surrounded shell-like by a zone of extinction and whose range is thus small relatively with respect to the range of sound waves ordinarily in use. Above the diaphragm a further conical region exists wherein sound waves are likewise perceptible. However, this region cannot usually be utilized for the transmission.

Such a sound field may for instance be pro-

duced in the manner that a loud-speaker system is used with a single diaphragm. But also several diaphragms may be provided, each of which is preferably driven separately and arranged in the manner that the one loud-speaker radiates in the one direction; the other loud-speaker in the opposite direction.

Care must be taken in all these constructions that a substantially equal sound field is produced on both sides of the diaphragm. Particular attention must be paid to this point with the use of a driving system with one diaphragm alone since the system must be throughout developed in the manner that the above mentioned demand regarding the sound field is met. If on the other hand two systems are chosen, the usual form of the loud-speakers may be employed and it is not necessary to construct the loud-speaker differently from the usual form in order to suit the mentioned purpose.

In the case of the use of two loud-speaker systems, one system will for instance be arranged in the manner that its diaphragm radiates substantially downward, while the diaphragm of the other system radiates upward. The directions of the axes of the diaphragms coincide. The two systems are installed in an acoustically closed space. The diaphragms form part of the walls of this space. The one side of each diaphragm acts upon the outer air and in such manner that the diaphragms vibrate in counter rhythm, with respect to the outer sound field. In other words, if these two systems are considered as a joint unit, the air is attenuated at the front side in front of one diaphragm and densified in front of the other diaphragm. Hence, from an electrical standpoint the diaphragms operate in phase opposition. However, from an acoustical point of view they operate in like phase, that is, in the same sense. A further requirement consists in that the diaphragms vibrate synchronously and with equal amplitudes. Accordingly, if one diaphragm moves away from the system, the other diaphragm moves towards the system. The reversal of both diaphragm movements occurs in the same instant. Such a structure with one or several systems shall be designated hereinafter as a push-pull twin radiator.

Exemplified embodiments of loud-speaker arrangements in accordance with the invention are disclosed in the appended drawings wherein Fig. 1 discloses a pair of loud-speaker units arranged to produce a horizontal zone of extinction in accordance with the invention, Fig. 2 is an explanatory diagram in connection with Fig. 1, Fig. 7 is a modification of Fig. 1 wherein the sound from a pair of loud-speaker units is radiated in the same direction, and Figs. 4 to 7 illustrate various modes of operation of a pair of loud-speaker units such as disclosed in Fig. 1.

Fig. 1 shows two loud-speaker systems 1, 2 of the usual dimensions located at a certain distance from each other in a pipe or housing 3 and whose diaphragms vibrate, looking from the outside, synchronously as indicated by the arrows. The arrangement is suitably attached to a mast 4. Two systems vibrating at different points must result everywhere in the sound field in interferences. Such interferences appear as such everywhere, for instance also in the propagation of sound in a reflecting closed chamber without making themselves felt in disturbing manner. But in the described push-pull twin radiator the central horizontal plane 5 has the distinction that all frequencies are extinguished therein. This extinction exists even within a certain angular range around this plane and the range is the greater the lower the reproduced frequency, hence the greater its wavelength.

The practical application of the push-pull twin radiator is accomplished in the manner that the radiators are installed at a certain height, for instance 5 meters, above the ground to be covered and with vertical axis, that is so that one loud-speaker radiates downward, the other upward. The audience assembled in the vicinity of the loud-speaker at the foot of the system, are then located sufficiently far away from the central plane of the push-pull twin radiator in order to receive an undisturbed sound field. The farther the hearer is from the foot point of the system, the nearer he comes to the range of extinction disposed around the central plane. This is shown in schematic manner in Fig. 2. Loud-speaker arrangement 6 is attached to a mast which in turn rests on the ground.

As explained before, the extinction is particularly effective with low frequencies, in fact with a mutual distance of the systems of 50 centimeters there results in this arrangement at a greater distance a sufficient attenuation, up to about 1000 cycles. The region of extinction is widened with lesser distance between the loud-speakers towards the high frequencies and inversely. On the other hand, the extent of the undisturbed hearing range depends on the mutual distance of the systems in the push-pull twin radiator and on its height above the ground to be covered. Thus as easy means is given for adaption to conditions prevailing at a particular moment, or case.

For good efficiency it must be presupposed that the radiation is as much as possible equal for both individual loud-speakers. Regulating arrangements may be provided for maintaining this condition.

Since the push-pull twin radiator has proved suitable as close-action loud-speaker, particularly for medium and low frequencies, it is to be recommended to impress on it only the frequency band for which it has its characteristic properties, thus for instance for a frequency band of 0 to 500 or 1000 cycles. The frequencies above these are then to be radiated by special loud-speakers which may be connected with a push-pull twin radiator to a constructional unit and directed by means known in the art in the manner that their covering range does not exceed that of the push-pull twin radiator. Since this is then merely a case of short wavelengths, the condition can be sufficed with arrangements of small dimensions.

Fig. 3 represents a push-pull twin radiator where the sound radiated by the individual sys-

tems emerges in one direction only. Loud-speaker systems 31 and 32 are enclosed in a pipe-like housing 33. In front of loud-speaker systems 31 and 32 are further arranged sound guides 37. These latter, if necessary of conical form, have openings 38 arranged in the same direction. The loud-speaker arrangement is attached to a mast 34.

This arrangement insures a propagation of the low frequencies on all sides, but whose range 10 is restricted due to interference. On the other hand, the high frequencies spread asymmetrically.

Figs. 4 to 7 illustrate in schematic manner exemplified embodiments for operation of push-pull 16 twin radiators whereby the membranes of the loud-speaker arrangement do not exactly vibrate in opposite rhythm so that zones of extinction are obtained deviating from the conical shape as indicated in Figs. 1 and 2. In Figs. 4 to 7 the 20 same symbols are chosen for the same elements.

In the embodiment according to Fig. 4, a mast 41, set on the ground, has attached loud-speaker arrangement 42. The loud-speaker arrangement consists of a pipe-like housing 43 at whose ends 25 are placed loud-speakers 44 and 45. Housing 43 is suitably arranged in the manner that it may be lengthened or shortened. Thus is provided an easy way to adjust the distance between the loud-speakers. The region of extinction starts 30 between the two loud-speakers 44 and 45 and its axis 46 has a hyperbolic form. The region of extinction is located approximately between curves 47 and 48 above and below axis 46.

When housing 43 is rotatably attached to mast 41, a sound field is obtained as shown in Fig. 5. This furnishes the means to avoid excessive sound intensities at the foot point.

The rotatable arrangement has the further advantage that the sound field may be adapted to 40 local conditions. An application therefor is illustrated in Fig. 6. The loud-speaker arrangement is set up in an open-air theater, arena or other inclined ground 49. As may be seen from the sound field, the arrangement can be adjusted 45 in the manner that a particularly favorable adaption to ground conditions is insured.

Fig. 7 represents a further application of the arrangement according to invention. In broadcast or speech-amplifying installations, where 50 microphones are often set up in the vicinity of the loud-speakers, the difficulty is encountered how to avoid acoustic reactive actions. In a loud-speaker arrangement according to the invention the microphone in action is disposed in the range of the zone of extinction, thus eliminating the danger of a back-coupling. Microphone 58 is indicated in perfectionary manner.

What I claim is:

A loud-speaker system wherein the distribution of the radiated sound waves may be controlled, comprising a housing, a pair of loud-speaker units mounted coaxially within said housing and faced in opposite direction to each other, means for actuating said loud-speaker units in substantially opposite electrical phase and in substantially like acoustical phase whereby there is produced a fan-shaped zone of extinction which surrounds the common axis of the units and extends at right angles thereto, and means for adjusting the position of the housing in a vertical plane for altering the pattern of the sound distribution in a desired manner.
